UNITED STATES PATENT OFFICE

LANEY D. HERNDON, OF COLUMBUS, GEORGIA

WINDOW SCREEN

Application filed May 8, 1929. Serial No. 361,471.

This invention relates to a window screen, the general object of the invention being to provide a screen which is adapted to be placed in the outer part of a window frame, with means whereby the screen is hingedly and detachably connected with the top of the frame so that the screen can be opened by swinging it outwardly from the bottom and can be removed from the frame without difficulty.

10 A further object of the invention is to provide simple means for holding the screen in the frame of the device.

This invention also consists in certain other features of construction and in the combination and arrangement of the several parts, to be hereinafter fully described, illustrated in the accompanying drawings and specifically pointed out in the appended

20 claims.

In describing the invention in detail, reference will be had to the accompanying drawings wherein like characters denote like or corresponding parts throughout the several views, and in which:—

Figure 1 is an exterior view of a window frame, showing the improved screen in place.

Figure 2 is a section on line 2—2 of Figure 1.

30 Figure 3 is a section on line 3—3 of Figure 1.

Figure 4 is a sectional view through a part of the screen.

In these views, the numeral 1 indicates the frame of the screen, the screen being shown at 2, and 3 indicates the frame of the window. A pair of brackets 4 is fastened to the top edge of the screen frame, the upper part of each bracket having an opening therein and a pair of brackets 5 is fastened to the outer face of the top part of the window frame. Each bracket has its central part of substantially U shape, as shown at 6, with an upward extension 7 on the bight of the U and the limbs of each U are notched at their upper edges so that a space is formed by said notches and the extension 7 to receive the top part of the bracket 4 when the opening in the bracket is passed over the U-shaped part 6. Thus the screen frame is

hingedly connected with the window frame by these brackets and the screen frame can be easily and quickly removed from the window frame by simply pushing the screen frame out of the window frame and then lifting it so that the brackets 4 will clear the extensions 7. The hinge arrangement permits the screen to be swung outwardly from the window frame and it is held in closed position by a hook 8 connected with the lower part of the screen frame and engaging an eye 9 on the sill of the window.

The screen frame is formed with a flange 10 which fits within the window opening and the outer part of the screen frame fits against the outer face of the window frame so that the screen will fit various sizes of window frames. The screen frame is also formed with a second flange 11 which is spaced from the first flange and the mesh 12 is adapted to have its edges depressed into the space between the two flanges and the mesh is held in this space by the U-shaped filler strips 13 which are pressed into the space between the two flanges and act to clamp the edges of the mesh into said space. The filler strips are held in the space by the screws 14 which pass through the strips and the flanges. The screen frame may be provided with a centrally arranged cross bar 15 to which is bolted a channeled cross bar 16 which acts to press the central part of the screen against the bar 15.

From the foregoing it will be seen that I have provided a window screen, all parts of which are formed of metal and one in which the mesh is securely held in place, but which can readily be removed when worn and replaced by a new mesh. The screen frame can be easily opened and closed from the inside of a window and it can also be removed from the window frame when desired.

It will, of course, be understood that the screen can be used for a door opening as well as a window opening.

It is thought from the foregoing description that the advantages and novel features of the invention will be readily apparent.

It is to be understood that changes may be made in the construction and in the combina-

tion and arrangement of the several parts, provided that such changes fall within the scope of the appended claims.

What I claim is:—

- 5 1. A screen of the character described comprising a rectangular one-piece metallic frame including a relatively wide flat body portion having its inner edges bent to provide a right angularly disposed flange, a
- 10 second flange projecting inwardly from the frame spaced from and in parallelism with the first mentioned flange, both of said flanges being spaced inwardly from the edges of the window opening when the screen is in use,
- 15 a wire fabric having its marginal edges bent between said flanges, and a substantially U-shaped filler strip positioned between the flanges for clamping the wire fabric therebetween and lined substantially flush with the free edges of said flanges.
- 20 2. A window screen of the character described comprising a one piece substantially rectangular shaped frame, including a relatively wide flat body portion adapted to bear against the face of the window casing, and having its inner edge extended to provide a right angularly disposed flange, a second flange projecting from one side of the body portion and arranged about in spaced parallel relation to the first mentioned flange, a
- 25 wire fabric having its marginal edges bent in the spaces between said flanges, a substantially U-shaped filler strip received between said flanges for clamping the fabric to the frame and lined substantially flush with the free edges of the flanges, a transverse bar supported by the first mentioned flanges centrally of said frame, and bearing against one side of the wire fabric, and a channel cross bar bearing against the opposite side of the fabric and connected with the said transverse bar, and said flanges of the frame being spaced inwardly from the adjacent edges of the window opening when the screen is in use.

In testimony whereof I affix my signature.
LANEY D. HERNDON.
